ATTORNEY

UNITED STATES PATENT OFFICE.

JOSEPH A. SMITH, OF ATTLEBORO, MASSACHUSETTS.

NURSING NIPPLE.

Application filed December 20, 1926. Serial No. 155,998.

My invention relates to an improved nursing-nipple characterized in that the nipple is non-collapsible and does not descend into the neck of the nursing bottle.

5 It is a familiar fact that the ordinary nursing nipples of commerce possess the undesirable feature of collapsing in use due to the partial vacuum which by the sucking of the infant is created, all to the annoyance and 10 disturbance of the infant who is generally made fretful thereby. Another evil to which the nipples now in use are subject arises after the nipple becomes extremely flexible from use so that it is thrust down the neck of 15 the nursing bottle with facility by the infant. Both these evils do much to deprive the infant of a portion of the pleasure which generally accompanies feeding.

Many attempts have been made to solve 20 the problem presented by the evils specified and in fact many forms of nipples have been proposed and patented but none has as yet met with universal acceptance as accomplishing the sought for result.

25 It is an object of my invention to provide a nursing-nipple, simple in design and effective in operation which permits the uninterrupted flow of fluid to the infant, regardless how far the nipple is pulled down 30 over the bottle neck.

Another object of my invention is to provide an improved nursing nipple having therein a bridge member which has the double function of preventing the formation of a 35 partial vacuum and also serves to prevent the nipple top from being pushed into the neck of the bottle.

Other objects and advantages will appear from the following detailed description.

40 I attain these objects by the mechanism illustrated in the accompanying drawing, in which—

Fig. 1 is a bottom view of my improved nipple showing the interior of the socket 45 with the bridge member in place.

Fig. 2 is a front elevational view of the nipple in inverted position showing the bridge member extending over the bead portion of the nipple.

50 Fig. 3 is a cross sectional view taken along line A—A of Fig. 2 showing in a clearer fashion the relation and disposition of the bridge member within the socket of the nipple.

55 Fig. 4 shows my improved nipple applied to a nursing bottle, the nipple and bottle

neck being shown in cross section for the sake of greater clarity.

Fig. 5 is a view taken along line B—B of Fig. 4 showing the bridge member distended 60 across the mouth of the bottle as well as the air ducts formed at the side of the bottle neck by the end of the bridge member disposed between the socket and the bottle neck.

Fig. 6 shows cross sectional view of a 65 modification wherein the bridge has a right angular contour.

Referring to the drawing, 1 designates the bead on the nursing nipple, 2, the socket which is generally of a lesser diameter than 70 the neck of the bottle to ensure a close fit, 3 the shoulder portion of the socket, 4 the closed end or nipple proper, 5 the hole in the extremity for egress of the fluid and 6 the diagonal bridge member which extends from 75 a point adjacent the interior of the shoulder portion to the outside of the bead.

So far as the exterior of the nipple itself is concerned, the structure is unchanged. I may take any nipple now to be found in use 80 and equip it in the manner hereinafter suggested and achieve the desired results. By taking a narrow strip of rubber or similarly extensible material and adhering one end thereof to the interior of the wall portion of 85 the socket 2 adjacent the shoulder 3, as shown in Fig. 3, and adhering the other end around the bead portion 1, a nipple having a bridge piece diagonally disposed therein, is produced. The length of the strip should 90 be sufficient to enable the strip to extend in the manner shown but it should not be stretched when applied to the nipple.

When in use this bridge member is stretched across the top of the bottle, as shown in 95 Figs. 4 and 5. When in place on the bottle the wall portion 7 of the socket 2 against which the bead end of the bridge member 6 presses, does not hug the bottle tightly by reason of the bridge member which acts as a 100 buffer, leaving narrow air ducts or clearances 8, 8, which extend from the mouth of the bottle to the bead portion. Since the bridge member envelops the bead at its point of contact, the continuity of the air 105 ducts is made possible. The size and extent of the air ducts may be varied according to the thickness and width of the bridge member. It is preferable to employ a very narrow bridge member so as not to interfere 110 with the flow of fluid from the bottle.

The material of which the bridge member

is made may be rubber or any other suitable material.

In the modification shown in Fig. 6 the bridge member 9 is transversely disposed within the socket but instead of extending diagonally as in Fig. 3, it extends diametrically of the socket at the shoulder portion thereof, with one end continuing along the wall of the socket and ending outside of the bead portion.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure which utilize the principle of my invention and fall within the purview of my invention and are within the spirit and scope of the following claims.

The invention having been set forth, what is claimed as new and useful is:

1. In combination with an elastic nursing nipple having an expandible socket, an elastic bridge member disposed within and

secured to the interior of said socket, said elastic bridge member extending transversely of said socket, one end of said bridge member being secured at a point outside the edge of said expandible socket.

2. An elastic nursing nipple comprising in combination an expandible socket, said socket having a wall adapted to yieldingly embrace a bottle neck, a bridge member secured at one end of said wall at its upper portion and extending transversely of said socket, the other end of said bridge member being secured to the outer side of said socket wall adjacent the base.

3. An elastic nursing nipple comprising an expandible socket, a body portion, a shoulder intermediate of said socket and body portion, an extensible bridge member disposed transversely within said socket, said bridge member being secured at one end to the interior of said nipple adjacent the shoulder thereof, the other end being secured at a point outside the edge of said expandible socket.

Signed at Fall River in the county of Bristol, State of Massachusetts, this 22nd day of October, 1926.

JOSEPH A. SMITH.
